UNITED STATES PATENT OFFICE.

SHOZO MIURA, OF NEW YORK, N. Y.

DESIGN FOR A LAMP STAND.

Application filed May 8, 1922. Serial No. 2,128. Term of patent 3½ years.

To all whom it may concern:

Be it known that I, SHOZO MIURA, a subject of the Emperor of Japan, residing at New York city, in the county of New York and State of New York, have invented a new, original, and ornamental Design for Lamp Stand, of which the following is a specification, reference being had to the accompanying drawings, forming part thereof, in which—

Fig. 1 is a top plan view of a lamp stand showing my design.

Fig. 2 is a front elevation of the same and Fig. 3 is a side elevation of the same.

I claim:

The ornamental design for a lamp stand as shown.

SHOZO MIURA.
